2,398,000

MANUFACTURE OF YARN

Malcolm Hain, Montclair, N. J.

Application February 2, 1944, Serial No. 520,766

5 Claims. (Cl. 19—130)

In my Patent No. 2,197,638 I have set forth a novel mechanism for drawing a sliver composed of jute or other bast fibers whereby, without the use of gills, the sliver may be brought to proper state for spinning. Given the usual drawing and retaining roll-pairs and a so-called driven roll between such roll-pairs, in that case a pair of freely rotative rolls were held yieldingly urged toward the driven rolls and free to turn as a pair around an axis parallel with the axis of the driven roll, whereby to coact with the driven roll to exert pressure on the sliver thus to cause fibers not actually nipped by the drawing rolls to be held against advance merely by fibers actually so nipped. According to the present invention the result thus accomplished by my said patented mechanism is also accomplished by a mechanism simpler in construction.

In the drawing:

Fig. 1 is a side elevation, partly in section, of a drawing mechanism embodying the present invention; and

Fig. 2 is a plan of the rolls 11—11a and the means 29—30 for maintaining roll 11a in coactive pressure-exerting relation to roll 11.

Let 1 be a part of the frame of the machine. At 2 and 2a are the drawing rolls, roll 2 being fast to the shaft 3, and roll 2a having its trunnions resting on guideways 1a of the frame which project toward roll 2 and said roll 2a being held pressing against roll 2 by a lever 4 assumed to carry a weight (not shown) and fulcrumed in a bracket 1b of the frame, the lever exerting its pressure on the roll through a plunger 5. At 6—6a are the as usual fluted retaining rolls above the drawing rolls, roll 6 being fast to a shaft 7 and roll 6a being journaled in the forked forward end of a lever 8 fulcrumed in the frame and, due to a weight 9 carried by the lever, serving to press roll 6a against roll 6. Between the drawing and retaining roll pairs and fast to a shaft 10 is what I herein term a driven roll 11 against which is made to bear, as will appear, what I term a pressure roll 11a. By usual gearing the rolls 2 and 6 are driven, thus: Shaft 3 being suitably driven, a gear 12 thereon meshes with a gear 13 formed as a unit with a gear 14 which meshes with a gear 15 on shaft 7. Gear 15 is in effect a unit with a gear 16 which meshes with a gear 17, in turn meshing with a gear 18 on shaft 10 of the driven roll whereby the latter is driven. The sliver *a* passes over a suitable guide 19 at the top of the frame and a forked guide 19a, down between the rolls of the pairs 6—6a, 11—11a and 2—2a in the

order named, but between the last two pairs through a spout 20, and finally through a grooved guide 21 to and through the cap 22 of the spinning unit.

5 The bracket 23, clamping member 24, handlever 25 to coact with member 24 to clamp the sliver, the bell-crank lever 26, link 27 and link 28 having a projection 28a under lever 8 are all substantially the same as in my Patent No. 2,197,638.

10 Pressure roll 11a is supported by what is in effect a slideway 29a lateral of the driven roll 11 and here afforded by the upper surfaces of arms of a bifurcated bracket 29 which is a fixed projection of a rail 1c of the machine frame, said 15 bracket straddling the roll 11a, whose trunnions rest on the slideway, which in this example is pitched downwardly toward roll 11.

At 30 is a lever having a forked forward end which straddles roll 11 and whose forked terminals receive shaft 10 on which such lever is thus fulcrumed. The lever also has what is in effect a slideway 30a here afforded by the under surfaces of its arms which rest on the trunnions of roll 11a, this slideway being here pitched downwardly from roll 11. Remote from its fulcrum 25 the lever is here bent downward and then rearward, its free end supporting a weight 31. Link 28 is connected to this lever. The lever may have a sliver guide in the form of a fork 30b.

30 The surfaces forming the slideways provide bearings for the pressure roll.

By the gearing shown the drawing rolls 2—2a are rotated at a greater speed than the retaining rolls 6—6a and the roll 11 of the pair 11—11a is rotated at a speed between those of the drawing and retaining rolls.

35 In operation, with the pressure roll 11a and lever 30 in the position shown, the rolls 11—11a coacting to compress the sliver *a* at a point between the drawing and retaining rolls, those fibers of the sliver which are not nipped by the drawing rolls exist compressed by the rolls 11—11a, of which roll 11 is rotated more slowly than the drawing rolls, and so are held against advance incident merely to such bond as exists between them and those actually so nipped, wherefore the drawing proceeds uniformly, or without bunching.

If the sliver parts between the drawing rolls and the spinning unit it is desired, as in my said patent, to stop the drawing and consequent delivery of the sliver. For this purpose, lever 25 is moved toward the dotted position so as to clamp the sliver and retract roll 6a and also lever 30. 55 This leaves only the weight of roll 11a effective

to cause rolls 11—11a to clamp the sliver, wherefore the latter parts as an incident of the clamping, as in my said patent, in convenient proximity to the drawing rolls.

My invention is characterized by including, with a pressure roll having its axis substantially parallel with the axes of the drawing and retaining rolls and the driven roll, members having bearing surfaces engaging the pressure roll and converging from the sliver being drawn and normally holding said pressure roll against the driven roll and one of which members is yieldingly urged toward the other, and one of which members underlies the pressure roll and has its said surface inclined downwardly.

Having thus fully described my invention, what I claim is:

1. A sliver drawing mechanism including, in combination, supporting means, drawing and retaining means including, respectively, a pair of drawing rolls and a pair of retaining rolls journaled in the supporting means, a driven roll journaled in said supporting means substantially between said pairs, said supporting means having a slideway lateral of and extending and inclined downwardly toward the driven roll, a pressure roll resting and free to move on the slideway against the driven roll, all said rolls being arranged to maintain the portion of the sliver undergoing draft in upright state and having their axes substantially horizontal, means to rotate one drawing roll and one retaining roll, the former at the superior speed, and also rotate the driven roll at a speed between those of the latter drawing and retaining rolls, and means normally urging said pressure roll toward the driven roll.

2. The combination set forth in claim 1 characterized by the last-named means including a lever fulcrumed in the supporting means and engaging the pressure roll.

3. A sliver drawing mechanism including, in combination, supporting means, drawing and retaining means including respectively, a pair of drawing rolls and a pair of retaining rolls journaled in the supporting means, the latter pair being above the former pair, a driven roll journaled in said supporting means substantially between said pairs, said supporting means having a slideway lateral of and extending and inclined downwardly toward the driven roll, a pressure roll resting and free to move on the slideway against the driven roll, means to rotate one drawing roll and one retaining roll, the former at the

superior speed, and also rotate the driven roll at a speed between those of the latter drawing and retaining rolls, all said rolls having their axes substantially parallel, and means, including a lever fulcrumed in the supporting means and having a slideway engaging the pressure roll and converging toward the first-named slideway in a direction from the driven roll, normally urging said pressure roll toward the driven roll.

4. A sliver drawing mechanism including, in combination, supporting means, drawing and retaining means including, respectively, a pair of drawing rolls and a pair of retaining rolls journaled in the supporting means, a driven roll journaled in said supporting means substantially be-

tween said pairs, said supporting means having a slideway lateral of and extending and inclined downwardly toward the driven roll, a pressure roll resting and free to move on the slideway against the driven roll, all said rolls being arranged to maintain the portion of the sliver undergoing draft in upright state and having their axes substantially horizontal, means to rotate one drawing roll and one retaining roll, the former at the superior speed, and also rotate the driven roll at a speed between those of the latter drawing and retaining rolls, means normally urging said pressure roll toward the driven roll, and means to retract the last-named means from said driven roll and the other of the retaining rolls from the first-named retaining roll and simultaneously brake the sliver relatively back of said retaining rolls.

5. Mechanism for drawing sliver including supporting structure, a pair of drawing rolls, a pair of retaining rolls and a driven roll substantially between said pairs, all said rolls having their axes substantially parallel, and means to rotate one drawing roll and one retaining roll, the former at the superior speed, and also rotate the driven roll at a speed between those of the latter drawing and retaining rolls, said mechanism also including, with a pressure roll having its axis substantially parallel with said axes, members having bearing surfaces engaging the pressure roll and converging from the sliver being drawn and normally holding said pressure roll against the driven roll and one of which members is yieldingly urged toward the other, one member underlying the pressure roll and having its bearing surface inclined downwardly.

MALCOLM HAIN.
